UNITED STATES PATENT OFFICE.

FRANK S. RECE, OF DALLAS, TEXAS.

CRIB-SPRING SUPPORT.

Application filed April 7, 1924. Serial No. 704,817.

This invention relates to new and useful improvements in spring supporting and elevating means for cribs.

In using cribs alongside of beds it is 5 desirable to elevate the mattress of the crib, so that it is substantially flush with the mattress of the bed. It is also important that the spring supporting the mattress may be lowered as readily and as easily as it is 10 elevated, both in registering it with the bed mattress and for other purposes.

The object of the invention is to provide a simple and expeditious means for elevating the mattress supporting spring of a crib, 15 with a minimum effort and whereby the spring is automatically held at the elevation to which it is adjusted.

A further object is to provide means for releasing the spring supports so that the 20 same may be lowered in an easy, simple and expeditious manner.

Another object of the invention is to provide means for elevating and for lowering the mattress support, which is accessible and 25 operable without lowering or adjusting the side and end panels of the crib.

A construction designed to carry out the invention will be hereinafter described together with other features of the invention. 30

The invention will be more readily understood from a reading of the following specification and by reference to the accompanying drawings, in which an example of the invention is shown, and wherein:—

35 Fig. 1 is a plan view of a crib having a mattress spring constructed in accordance with my invention,

Fig. 2 is a side view of the same, the side panel of the adjacent side being lowered,

40 Fig. 3 is a transverse vertical sectional view,

Fig. 4 is an enlarged detail of the releasing means,

45 Fig. 5 is a transverse vertical sectional view showing the mattress of a crib elevated flush with the mattress of a bed, and

Fig. 6 is a detail in elevation of the releasing means.

In the drawings the numeral 10 designates the frame of a crib which is suitably mounted on wheels 11, so that it may be moved from place to place. End panels 12 and side panels 13 are suitably mounted on the frame for folding or otherwise. 55 Longitudinally of the frame and spaced above its bottom are a pair of supporting

rails 14. Near each end each rail has a toothed ratchet bar 15 secured to its side, so that the teeth of the bars project above the rails.

A spring or mattress support comprises a frame 16 carrying a resiliently supported fabricated panel 17 or any suitable bed spring structure. At each end of the frame 16 is pivoted a supporting bail or yoke 18 having a transverse connecting bar 19. The bails are pivoted to swing inwardly under the spring so that when the spring is fully lowered the bars 19 will rest upon the rails 14. When either end of the spring is lifted 70 the bar 19 of the bail thereof, will trail along the rails and engage the teeth of the ratchet bars 15 and ride over the same as the lifting movement is continued. When the spring has been lifted to the desired elevation, it 75 will be held at this point by engagement of the bar 19 in the ratchet bars. The other end may then be adjusted to the same elevation.

Tabs 20 are fastened on the upper sides of 80 the ends of the frame 16 and to elevate the spring one merely has to lift the end of the mattress 21, grasp the tab and pull the spring upwardly. This is readily done without any great effort. By this arrangement it is possible to elevate the crib mattress until it is flush with the mattress 22 of the bed as is shown in Fig. 5. This is accomplished with ease and without disturbing the sides and ends of the crib. 85

It is desirable to lower the spring and mattress in a convenient and easy manner. For this purpose I provide for each bail a lever 23, which is pivoted to one side thereof and has its upper end bent outwardly at 90 right angles to form an arm 24 which overlies the side rail of the frame 16. A finger grip 25 is bent on the end of the arm. The arm slides on a plate 26 under a keeper 27.

When the frame 16 is raised to elevate the 100 mattress and the bail at that end swings relatively away from the frame, the lever 23 slides the arm 24 from the full-line position in Fig. 4 to the dotted line position. Thus when it is desired to lower the mattress frame it is merely necessary to slightly lift the frame which frees the bail from the teeth and then by sliding the arm 24 the lever will lift the bail, whereby the frame 16 may be lowered. This may be accomplished without disturbing the end or 105 side panels of the crib.

Too much stress cannot be laid upon the ease of operation of the elements of this invention and all parts must be made to work freely. Cribs are usually handled by women and therefore the spring frame 16 and the panel 17 should be of light weight and the bails 18 and levers 23 should be pivoted to swing readily and easily; whereby they may be manipulated with a minimum effort.

10 Various changes in the size and shape of the different parts, as well as modifications and alterations may be made within the scope of the appended claims.

What I claim, is—

15 1. In a crib, the combination of an adjustable frame, a swinging supporting bail upon the frame to engage retaining means on the crib, a lever pivoted to the bail, a keeper on the frame, and an arm on the lever disposed beneath the keeper to move in a plan parallel to the frame.

20 2. In a crib, the combination of a vertically adjustable mattress frame fitting snugly within the walls of the crib, supports pivoted to the underside of said frame, retain-

ing means engaged by said supports, and operating means connected to said supports and having a hand hold mounted for sliding and pivotal movement upon the upper face of the frame within the crib for raising said supports out of engagement with the retaining means and into folded position against the frame when the latter is lowered.

3. In a crib the combination of a pair of fixed rails, ratchet bars secured to said rails, and having their teeth projecting above the rails, a spring frame, bails having their ends pivoted to the ends of the spring frame and provided with transverse connecting bars 40 for riding along and engaging in the teeth of the ratchet bars when the frame is lifted, lifting levers having their lower ends pivoted to the bails and arms on their upper ends overhanging the spring frame and keepers for directing the travel of said arms parallel to the spring frame.

In testimony whereof I affix my signature.

FRANK S. RECE.
